UNITED STATES PATENT OFFICE.

THEODORE K. MACORN, OF ZEIGLER, ILLINOIS.

SHADE ROLLER AND CURTAIN FIXTURE.

Application filed May 20, 1924. Serial No. 714,626.

The invention relates to window fixtures for supporting shade rollers, curtain poles and the like and has for its object to prevent marring of the frame or casement and 5 to provide a fixture which may be adjusted within certain limits to different widths, said fixture also being adaptable for single or double windows.

Other objects and advantages will be apparent and suggest themselves as the nature of the invention is understood.

While the drawings illustrate an embodiment of the invention it is to be understood that in adapting the same to meet different 15 conditions and requirements, various changes in the form, proportion and minor details of construction may be resorted to without departing from the spirit of the invention.

Referring to the accompanying drawings 20 forming a part of the application:—

Figure 1 is a front view showing the application of the invention to a double window.

Figure 2 is a top plan view,

Figure 3 is an enlarged longitudinal section of one of the members,

Figure 4 is a transverse sectional view of a member,

Figure 5 is a detail view in perspective of an adjustable curtain rod,

Figure 6 is a detail perspective view of one form of curtain pole bracket, and

Figure 7 is a similar view of a modified form of bracket.

Corresponding and like parts are referred 35 to in the following description and designated in the several views of the drawings by like reference characters.

The fixture when adapted for single windows comprises two similar members and 40 when adapted for a double window embodies three similar members as indicated most clearly in Figures 1 and 2 of the accompanying drawings. In the adaptation for single windows, the middle member 45 shown in Figures 1 and 2 is omitted, the other members being attached to the sides of the window frame or casement.

Each of the members comprises a base plate 1 of sheet metal which is provided 50 upon its face with a longitudinal guide 2, formed by folding the metal on itself, as shown in Figure 4. The base plate 1 is of double thickness above guide 2, and the outer layer is cut out and has the side edges 55 of the cut out portions bent away from the inner layer to form sockets 3, the lat-

ter being disposed adjacent the top edge of the plate and adapted to receive curtain fixtures. The plate 1 may be provided with openings 4 to receive screws or other 60 fastening means whereby to attach the plate to the window frame or casement. The plate may also be provided at its outer end with a recurved portion 5 which is preferably toothed to engage the edge of the window 65 trimming and thereby obviate the use of screws, tacks, or like fastening means. Springs 6 are employed to draw the members together and hold the recurved end portions 5 in positive engagement with the window 70 trimming. Hooks 7 at the inner ends of the plate 1 receive the ends of the springs 6 which are engaged therewith.

A shade roller bracket 8 is provided for each base plate 1 and is slidably mounted in 75 the longitudinal guide 2 and comprises a base portion 8 and an offstanding portion 9, the latter having an opening to receive the journal of the shade roller in a manner well understood. A catch 10 mounted upon the base 80 portion 8 of the bracket is adapted to engage the teeth 11 of the plate 1 and hold the shade roller bracket in the required adjusted position. It is observed that the shade roller bracket may be applied to the base 85 plate 1 so that the offstanding portion 9 may be located at either end of the plate 1 as found most advantageous. One of the members is provided at its outer end with a ring 12 which provides convenient means 90 for stretching the springs 6 when placing the last member in position when fitting the fixture to a window.

Curtain pole brackets 13 are adapted to be fitted in the sockets 3 and may be of 95 different sizes and a hook 14 may be struck from each of the brackets 13 to engage and support a spring of the nature of the spring 6 and which is adapted to receive and support a curtain lambrequin or other drapery. 100 The curtain rod shown in Figure 4 comprises similar sections having sliding engagement and having the outer end of each bent and terminating in flanges 15 to engage selected sockets 3 whereby to retain the curtain rod in position when required for use. This adjustable curtain rod may replace the curtain pole brackets 13, or may be used jointly therewith if preferred.

It is to be understood that the members 110 comprising the fixture may be of any preferred construction and the middle member

is in effect a combination of the two members designed for a single window, since it performs the same office and is disposed between two windows of a double or twin window, as indicated most clearly in Figures 1 and 2.

What is claimed is:—

1. A curtain fixture comprising a base plate having a longitudinal guide on its face formed by portions of the plate spaced from the longitudinal edges and folded on itself and serving to reinforce the plate and to provide attaching portions outwardly thereof, marginal sockets struck out from one of said portions to reinforce same and adapted to receive supplemental fixtures, and a shade roller bracket adjustable in the longitudinal guide.
- 10
- 15

2. A curtain fixture comprising a base plate having a centrally disposed longitudinal guide on its face formed by portions of the plate spaced from the longitudinal edges and folded on itself and serving to reinforce the plate and to provide attaching portions outwardly thereof, marginal sockets struck out from one of said portions to reinforce same and adapted to receive supplemental fixtures, said base plate having teeth along the bottom of the longitudinal guide, a shade roller bracket adjustable in the longitudinal guide, and a catch carried by said bracket and adapted to cooperate with the teeth of the base plate to hold the bracket in the required adjusted position.

In testimony whereof I affix my signature.
THEODORE K. MACORN.
